LINED IGNITER-CHARGE TUBE

Leo T. Meister, Hillside, N. J.

Original application May 7, 1945, Serial No. 592,433. Divided and this application September 18, 1946, Serial No. 697,617

3 Claims. (Cl. 102—86.5)

(Granted under the act of March 3, 1883, as amended April 30, 1928; 370 O. G. 757)

1

The invention described herein may be manufactured and used by or for the Government for governmental purposes, without the payment to me of any royalty thereon.

The present invention relates to ammunition primers, particularly to the igniter tubes thereof.

An object of the invention is to provide an ammunition primer in which the igniter-charge, contained within the igniter-charge tube or body of the primer, is effectively sealed therein against the harmful influences of air, gases or liquids.

Another object of the invention is to provide an ammunition primer in which the interior liner for the igniter-charge tube is formed of a fusible thin-walled metallic seamless tube closed at one end.

A further object of the invention is the provision of a primer in which the liner, at or near its open end, is attached to the interior wall of the igniter-charge tube by an air-tight connection.

A still further object is to provide the liner of a fusible material such that it will intimately bond itself to the primer upon the application of heat.

A method of manufacturing the primer is disclosed in application Serial No. 592,433, filed May 7, 1945, of which the present application is a division.

Reference is made to the following description and accompanying drawing in which:

Figure 1 is a side view of a primer according to the present invention;

Figure 2 is a longitudinal central section of the primer taken on line 2—2 of Figure 1;

Figure 3 is an enlarged fragmentary central longitudinal sectional view of the primer illustrating the joint between the liner and the igniter charge tube; and

Figure 4 is a cross section taken through line 4—4 of Figure 1.

An igniter-charge tube 5 has at its firing end a head 6 which contains the usual percussion elements, not shown, and is threadedly attached to the igniter-charge tube 5 through screw threads 7 within the igniter tube 5. The threaded engagement between the tube 5 and the head 6 is sufficient to effect an air-tight connection. The igniter-charge tube 5 is provided with a number of vents or flame holes 8 for the passage of flame arising from the igniter-charge within the tube 5 when the primer is fired.

The igniter-charge tube 5 is advantageously made of brass and has located therein a thin-walled lead-tin alloy liner 10. This tube or liner 10 may be formed from a disk or slug of metal by drawing operations involving the use of a

2

punch and die, more or less in the same manner as cartridge cases are drawn from disks or cups of brass. The tube or liner 10 is seamless and has a closed and an open end. As it resembles an elongated sewing thimble having cylindrical walls, the tube or liner 10 is referred to herein and in the appended claims as "thimbles."

These thimbles may be made of any easily fusible suitable metal which is subject to plastic flow in drawing and which may be cemented or soldered within the igniter-charge tube, as hereinafter more fully appears. These thimbles are advantageously formed of tin or lead, or alloys of tin or lead, such as for example, an alloy consisting of 50% lead and 50% tin, or 60% lead and 40% tin.

In the further description which follows, the thimbles are considered as being made of or drawn from an alloy consisting of 60% lead and 40% tin, it being understood, however, that the invention is not confined to the use of this particular metal or alloy, as will be understood by the person skilled in the art. In practice, thimbles formed of alloys of lead and tin have proved to be very satisfactory.

The thimble 10 fits closely within the interior of the igniter-charge tube 5, covering all of the flame holes 8 thereof, with the closed end portions of the thimble 10 and the tube end 11 positioned adjacent each other and the open end of thimble 10 adjacent the imperforate portion of the igniter tube 5 located between the screw threads 7 and the openings nearest the said screw threads. Thimble 10 is inserted within the igniter-charge tube 5, as shown in Figure 2, and firmly pressed against the interior wall and closed end 11 of the igniter-charge tube 5 in any suitable manner, or as described in the aforementioned parent application Serial No. 592,433.

Prior to inserting the thimble 10 into the igniter tube 5, soldering flux is applied around the thimble 10 at the open end thereof. This flux, which is preferably a non-acid flux, extends around the thimble and along the length thereof for a short distance, for example a quarter or a half inch, from the open end of the thimble toward its closed end as diagrammatically indicated by "S" in Figure 3. Thus, the soldering flux lies between the wall of the thimble near its open end and the interior imperforate portion of the igniter-charge tube 5.

Localized heat of sufficient intensity is applied, as suggested by the aforementioned parent application Serial No. 592,433, to that area of the igniter-charge tube 5 near the open end of the thimble 10. The cylindrical wall of the thimble

melts during the heating, for an approximate length corresponding to the distance "S" of Figure 3, and owing to the fact that the thimble is made of a material which is a solder, it becomes soldered to the interior wall of the igniter-charge tube 5 upon cooling after the removal of the described heating. The soldering action extends completely around the thimble at or near the open end thereof, forming a gas-tight connection between the walls of the thimble near its open end and the adjacent imperforate portions of the igniter-charge tube 5 and the remainder of the walls of the thimble remain unattached to, but pressed against, the interior walls of the igniter-charge tube 5.

In loading the primer, a powder charge is inserted into the thimble 10, after it has been soldered into position, and the head 6, containing the percussion elements, not shown, is screwed into tight engagement with the screw threads 7. The primer is now ready for use in connection with fixed, semi-fixed or separate loading ammunition and upon the percussion elements in the head 6 being struck a flame is produced which ignites the powder charge within the fusible thimble 10. The burning of this igniter-charge produces a flame which melts the fusible thimble 10 and issues forth from the openings 8 to ignite the explosive or propellant charge with which the primer herein described is used.

As is clear to those skilled in the art, the thimble 10 may be formed of any metal that is readily fusible by the heat or flame produced by the burning of the igniter charge and which can be soldered to the igniter charge tube 5. A feature contained in the embodiment of the present invention resides in the use of a material for the thimble 10 which provides its own solder for soldering the thimble 10 at its upper end to the igniter-charge tube 5. In the event that the thimble 10 is formed of a metal which does not function as a solder, or when it is desirable to form a soldered joint in the customary manner, the exterior walls of the thimble near its open end are tinned, in a manner well known to the art, with an appropriate solder and the tinned portion coated with a soldering flux prior to inserting the thimble within the igniter-charge tube 5 and then applying heat as explained above.

A further advantage in using thimbles formed wholly or in part of tin, or comprising tin as a component of the metal thereof, is that the products from the destruction of the thimble by the burning of the igniter charge promotes or causes de-coppering of the bore or cannon. Thimbles made of soft metals such as tin or lead, or alloys thereof, are particularly advantageous in that

they may be made slightly smaller than the interior of the igniter-charge tube 5 and stretched or expanded into position to snugly fit against the interior wall of the igniter-charge tube 5.

5 This, of course facilitates and insures effective soldering in that upon application of heat, and due to the walls of the thimble near its open end being in such close relation with the interior walls of the igniter-charge tube 5, soldering takes 10 place practically at the instant that the open end of the thimble begins to melt. The solder from the melting end of the thimble immediately wets the adjacent interior walls of the igniter-charge tube 5 and upon removal of the heat, a 15 gas-tight joint is formed.

I claim:

1. A primer comprising a tube having an open and a closed end with the walls of said primer having a portion of the length thereof imperforate and the remainder of the length perforated, a thin-walled thimble of solder alloy in said tube having an open and a closed end adjacent corresponding ends of said tube, said thimble being secured to said tube at the imperforate portion thereof by said solder alloy and unattached to, but against, the perforated portions of said tube.

2. A primer comprising a tube closed at one end and having flame openings in its wall, a thin-walled metallic thimble within the tube with the closed end of the thimble adjacent the closed end of said tube, and the said thimble at its open end being soldered to the interior wall of said tube.

3. A primer comprising an igniter-charge tube closed at one end and having flame openings in its wall, a thin-walled lead-tin alloy thimble within the said tube with the closed end of the thimble adjacent the closed end of said tube, and the said thimble at its open end being soldered to said tube.
